(57) **CLAIM**

The ornamental design for an assembly and disassembly tool for faucet stream formers, as shown and described.

DESCRIPTION

FIG. 1 is a top-plan view of the assembly and disassembly tool for faucet stream formers in accordance with the present invention;

FIG. 2 is a right side view thereof;

FIG. 3 is a left side view thereof;

FIG. 4 is a rear view thereof;

FIG. 5 is a front view thereof;

FIG. 6 is a bottom view thereof;

FIG. 7 is a top-right-front perspective view thereof; and,

FIG. 8 is a bottom-right-front perspective view thereof.
